UNITED STATES PATENT OFFICE.

JOHN W. ZIMMERMAN, OF CHICAGO, ILLINOIS.

BOTTLE-CLOSURE.

No. 839,977.

Specification of Letters Patent.

Patented Jan. 1, 1907.

Application filed April 25, 1906. Serial No. 313,685.

To all whom it may concern:

Be it known that I, JOHN W. ZIMMERMAN, a citizen of the United States, and a resident of Chicago, in the county of Cook and State 5 of Illinois, have invented certain Improvements in Bottle-Closures, of which the following is a specification.

This invention relates to certain improvements in bottle-closures, and more particularly in that class of such devices which comprise pivotally-supported lids or covers adapted for movement into raised and lowered position, so that whenever desired such lids or covers may be raised to permit the contents 15 to be poured freely from the bottle and when such lids are lowered the bottles will be closed against the entry of insects, dust, and other impurities; and the object of the invention is to provide a device of this general 20 character of a simple and inexpensive nature and of a compact, strong, and durable construction having an improved arrangement of means for raising and lowering the lid or cover into opened or closed position.

25 The invention consists in certain novel features of the construction, combination, and arrangement of the several parts of the improved bottle-closure whereby certain important advantages are attained and the device is rendered simpler, cheaper, and otherwise better adapted and more convenient for use, all as will be hereinafter fully set forth.

The novel features of the invention will be 35 carefully defined in the claims.

In the accompanying drawings, which serve to illustrate my invention, Figure 1 is a side elevation showing the neck portion of a bottle having my improved closure applied 40 thereto with its lid or cover in closed position. Fig. 2 is a rear elevation showing the same parts. Fig. 3 is a view similar to Fig. 1, but showing the lid or cover in raised position; and Fig. 4 is a view similar to Fig. 1, 45 but showing the improved closure applied for use to the neck portion of a bottle of different form from that shown in Fig. 1.

As shown in the views, 1 indicates the neck portion of a bottle, herein shown as a 50 milk-bottle, since my improvements are especially adapted for use in connection therewith, and 2 indicates the usual fillet produced around the lips of such bottles, while 55 3 represents the attaching member of the improved closure, formed from sheet metal, with laterally-directed wings or arms 4 4

curved to conform to and clamp upon the opposite sides of the bottle-neck 1 and having sufficient elasticity so as to be capable of being sprung on and off the same for detachably 60 securing the improved closure in position for use.

The member 3 has an upwardly-extended and centrally-arranged portion 5 bent rearward so as to clear the lip 2 of the bottle-neck, and carrying at its upper end oppositely-projecting pivot lugs or pins 6 6, adapted for engagement in vertical slotted openings 7 7, produced in spaced ears 8 8, pendent from the rear pivotal portion of the 70 lid or cover 9, which is thereby held for pivotal movement upon member 3, so as to be adapted to be lowered into closed position, as shown in Figs. 1, 2, and 4, or into raised position, as shown in Fig. 3. For convenience in moving the lid or cover 9 the same is provided with a pendent thumb-piece or tongue 10 central between the spaced ears 8 8.

By means of the slotted connection of the lid or cover 9 with the attaching member 3 80 it is evident that a certain extent of vertical adjustment of said lid or cover is permitted with relation to the attaching member, so that the lid or cover is capable of being moved into opened or closed position despite variations in the position of the clamping-arms 4 4 upon the bottle-neck. In this way, as shown in Fig. 4, the device is caused to automatically accommodate itself to fillets of different depths, there being shown in said figure a 90 fillet 2 of greater depth than that shown in Figs. 1, 2, and 3.

The attaching member 3 is also provided with a centrally-arranged pendent pointed tongue or extension 11, extended below the 95 clamping-arms 4 4, and when the device is removed from the milk-bottle the pointed extremity of said extension or tongue is well adapted for use in removing the paper caps with which such bottles are commonly sealed. 100 When the device is in place upon the bottle-neck, the extension 11 is flush upon the rear side of the bottle-neck and interferes in no way with free handling thereof and at the same time affords a secure bearing of member 105 3, so that the same is more tightly held upon the bottle-neck.

From the above description it will be evident that the improved closure is of an extremely simple and inexpensive nature and 110 is especially well adapted for use upon milk-bottles by reason of the ease and convenience

with which it may be applied and removed and of the readiness with which it accommodates different styles of bottle-neck. The pointed extension 11 also further increases 5 the usefulness of the device for milk-bottles by affording means for conveniently removing the caps therefrom. It will also be obvious from the above description that the device is capable of considerable modification 10 without material departure from the principles and spirit of the invention, and for this reason I do not desire to be understood as limiting myself to the precise form and arrangement of the parts herein shown in carrying out my invention in practice. 15

Having thus described my invention, what I claim, and desire to secure by Letters Patent, is—

1. A closure for milk-bottles and the like 20 comprising two members, one of which is a cover adapted to close the mouth of the bottle and the other of which is a device adapted to be detachably secured upon the bottle, one of said members being provided with slots 25 and the other member being provided with pivot projections engaged for movement lengthwise of the slots to hold the members in hinged relation while permitting vertical adjustment of one member relatively to the 30 other.
2. A closure for milk-bottles and the like

comprising an attaching member having elastic arms to embrace a bottle-neck for detachable connection therewith, and provided with a central rearwardly and upwardly directed projecting portion the opposite sides of which have pivot projections and a lid or cover adapted to fit over the mouth of the bottle and having downwardly-directed lugs provided with vertical slotted openings 40 wherein the pivot projections of said first-named member are adjustably engaged and having a rearwardly-directed actuating-tongue extended from it between said lugs. 45

3. A closure for milk-bottles and the like 50 comprising an attaching member having oppositely-arranged elastic arms to embrace a bottle-neck for detachable connection therewith and provided with a central downwardly-directed pointed tongue midway between said arms and adapted to extend down along and bear upon the bottle-neck when said member is in place thereon and also adapted to penetrate a paper bottle-cap 55 when the member is detached from the bottle and a lid or cover hinged on said member.

Signed at Chicago, Illinois, this 27th day of February, 1906.

JOHN W. ZIMMERMAN.
